UNITED STATES PATENT OFFICE.

JOHN B. GROSS, OF HOBOKEN, NEW JERSEY, ASSIGNOR OF ONE-HALF TO
LOUIS FINKE, OF SAME PLACE.

TRAIN-STOPPING DEVICE.

SPECIFICATION forming part of Letters Patent No. 502,963, dated August 8, 1893.

Application filed November 22, 1892. Serial No. 452,792. (No model.)

To all whom it may concern:

Be it known that I, JOHN B. GROSS, of Hoboken, in the county of Hudson and State of New Jersey, have invented a new and Improved Train-Stopping Device, of which the following is a full, clear, and exact description.

The invention relates to improvements in railroad signals by which a moving train is stopped automatically when moving into proximity of an open switch, draw or other point of danger.

The object of the invention is to provide a new and improved train stopping device which is simple and durable in construction, and arranged to automatically shut off the steam from locomotive engines, and to apply the air brakes so as to bring the train to a standstill.

The invention consists of certain parts and details and combinations of the same, as will be fully described hereinafter and then pointed out in the claims.

Reference is to be had to the accompanying drawings forming a part of this specification, in which similar letters of reference indicate corresponding parts in all the figures.

Figure 1 is a side elevation of the improvement with parts in section. Fig. 2 is an end elevation of the same. Fig. 3 is a transverse section of the same on the line 3—3 of Fig. 1. Fig. 4 is a sectional side elevation of the lever for operating the air outlet valve. Fig. 5 is a plan view of the shaft pulley for the arm. Fig. 6 is an enlarged side elevation of the mechanism for setting the arm. Fig. 7 is a transverse section of the same on the line 7—7 of Fig. 6. Fig. 8 is a like view of part of the same on the line 8—8 of Fig. 7. Fig. 9 is a rear face view of the setting lever. Fig. 10 is a face view of a collar for the said setting lever. Fig. 11 is a face view of the covering plate for the setting mechanism. Fig. 12 is a side elevation of the device for operating the throttle lever, parts being shown in section; and Fig. 13 is an end view of the same.

On the tender A' for the locomotive A of any approved construction, is secured a standard B provided on its upper end with guideways B' in which is fitted to slide vertically a cross-head C carrying a downwardly-extending arm C' pivotally connected with a

rod C², extending through an opening in the tender, as is plainly shown in Fig. 1. The lower end of this rod C² is formed with a head C³, engaging a casing C⁴ loosely mounted on a collar C⁵ secured to one of the axles A² of the tender A'.

On the upper end of the cross-head C is supported a cylinder D, provided with an air inlet tube D' connected by a flexible hose E' with the main train pipe E of the train, and belonging to a fluid pressure brake of any approved construction. The cylinder D is also provided in its bottom with an opening D² leading to the outer air, as is plainly shown in Fig. 4. The inner end of the tube D' is normally closed by a valve D³, secured on the transversely-extending shaft D⁴, passing centrally through the cylinder D and journaled in the heads of the said cylinder, as will be readily understood by reference to the drawings. On the outer ends of this shaft D⁴ is secured a lever F, preferably made U-shaped, as is plainly shown in Fig. 3, the said lever extending upward and carrying at its upper end a point F' adapted to be engaged by an arm G secured on a transversely-extending shaft G' journaled in suitable bearings in a frame or bracket H preferably made U-shaped and attached to some of the ties of the railroad track. The frame H extends over the track, as is plainly shown in Fig. 2, so that the train with the locomotive A and the tender A' passes through the said bracket to bring the arm G into the path of the point F' in case danger is ahead for the train.

The point F' is made hollow and carries a pin F² pressed on by a spring F³, so that the lower end of the pin F² is adapted to engage a recess C⁶ formed in a segment C⁷ attached to brackets on the cross-head C. When the lever F stands vertically, as shown in Fig. 1, the point F' is in the path of the arm G, so that the latter is struck by the point F' at the time the locomotive passes through the bracket H, whereby the lever F is swung to one side, thereby turning the shaft D⁴, so that the valve D³ uncovers the opening of the tube D', and part of the air from the air brake is discharged into the cylinder D and passes out of the same through the opening D² to the outer air. As soon as it is discharged from the main pipe

E the brakes are applied in the usual manner and consequently the train is brought to a standstill.

The arm G is connected with a switch located ahead of the bracket H, or with a draw or other point of danger in the roadbed. Now, in order to actuate the said arm G, so that it will stand in position to strike the point F' at the time the switch or the draw is open the following device is provided: On the shaft G' is secured a pulley G², on which are secured the ends of a rope I, each end of the latter passing several times around the said pulley and then extending downward and passing over a series of pulleys H' secured on one side of the bracket H, as is plainly shown in Figs. 1 and 2.

The strands of the rope I pass under pulleys H² and H³, held on an auxiliary frame II⁴ attached to one side of the bracket H, and then the strands extend upward and wind on a drum J secured on a shaft J' extending transversely in a housing H⁵ secured to the auxiliary frame II⁴, as is plainly shown in Fig. 7. By reference to the latter figure, it will be seen that the strands of the rope I pass upon the said drum in opposite directions, so that when the drum is turned one of the strands is wound up, while the other unwinds from the said drum, and a like motion takes place on the pulley G², so that the shaft G' is turned in the same direction as that in which the shaft J' is turned. This shaft J' is connected with a switch or draw, and is provided for this purpose with a pulley K on which is secured a chain or rope K' extending downward and having its ends connected with arms K² and K³ secured on a transversely-extending shaft K⁴ journaled in suitable bearings attached to the ties carrying the bracket H, see Fig. 2. On this shaft K⁴ is secured another arm K⁵ pivotally connected with a link K⁶ extending to the switch lever or to the draw to enable the operator to open or close the switch or to lock and unlock the draw.

The shaft J' is adapted to be actuated by the operator in charge of the switch or draw, and for this purpose a hand lever L is provided which is pivoted at L' to a collar L² mounted loosely on the shaft J', see Figs. 7 and 9. On the rear side of the lever L is secured a lug L³ adapted to engage a notch H⁶ formed in an annular flange H⁷ secured on one of the covering plates of the housing H⁵. The lug L³ is also adapted to engage a notch H⁸ formed diametrically opposite the notch H⁶ on the top of the flange H⁷, as shown in Fig. 11. A spring L⁴ presses on the front side of the lever L, so as to hold the lug L³ in contact with either of the notches H⁶ or H⁸. In order to engage the lug L³ with the notch H⁸, the hand lever L is given a half-turn in an upward direction, either to the right or left. When the hand lever L is moved into this uppermost position, the switch is closed or the draw is locked and no danger is ahead for the train. A second lug L⁵ is arranged

on the front side of the hand lever L directly opposite the lug L³ and this lug L⁵ is adapted to engage the notch L⁶ formed in a flange L⁷ forming part of the collar L² previously mentioned and shown in Fig. 7. On the upper end of this flange L⁷ is held a stud L⁸ on which is fulcrumed a pointer N adapted to engage with its lower rounded end N' (see Fig. 6), a recess J² formed in the collar J³ secured by a key or other means to the main shaft J'. The lug L⁵ previously mentioned is adapted to pass through the notch L⁶ into a recess J⁴ formed on the inner face of the collar J³, the said recess being located diametrically opposite the recess J², as plainly shown in Fig. 10.

The pointer N is adapted to be locked to the flange L⁷ by a pin L⁹ passing through registering apertures in the pointer N and flange L⁷, as shown in Figs. 1, 2 and 9. This pin L⁹ is sheared off by the pointer N when the latter is turned on its stud L⁸ at the time the arm G is forcibly swung to one side when struck by a projection carried on the locomotive moving through the bracket, the said arm G then causing a turning of the drum J, shaft J' and collar J³, which latter engages the lower end N' of the pointer N. Now, when the several parts are in the position shown in Figs. 1, 2 and 9, then the lug L³ engages the notch H⁶ and when it is desired to turn the hand lever L into an uppermost position for the purpose of moving the arm G into a horizontal or "no danger" position, then the operator slightly swings the lever L outward to disengage the lug L³ from the notch H⁶ and to move at the same time the other lug L⁵ into engagement with the notch L⁶ in the flange L⁷ and within the recess J⁴ in the collar J³. The operator can then swing the lever L upward until the lug L⁵ registers with and snaps into the notch H⁸ on the top of the flange H⁷. By turning the lever upward, as described, the shaft J' is turned, thus imparting a traveling motion to the rope or chain I, so as to change the arm G from a vertical "danger" position to a horizontal "no danger" position.

When the switch or draw is open the lever L stands vertically downward, as shown in Figs. 1 and 2, so that the arm G extends likewise vertically downward into the path of the mechanism to be actuated and located on the locomotive, it being understood that the said mechanism also actuates the said arm to swing it from a vertical into a horizontal position, as hereinafter more fully described. When the hand lever L is in its lowermost position, the pointer N stands vertical, and is locked by the pin L⁹ to the flange L⁷ and the lever L is locked to the fixed flange H⁷ by the lug L³ engaging the notch H⁶ of the said flange as above described. Now, when the train moves along the track and comes to the bracket H located a suitable distance from the open switch or draw, then the arm G is struck by the point F', whereby the latter is moved to one side and away from the open-

ing of the tube D so as to permit part of the air in the train pipe E to escape, so as to apply the brakes and to bring the train to a standstill. When the switch or draw is closed 5 and in its normal position, then the lever L is in an uppermost position so that the arm G swings into a normal horizontal position and consequently out of reach of the point F'. The train then moves along without the 10 point F' striking the arm G at the time the tender passes the bracket H. When the arm G, however, is in a lowermost position, then the forcible swinging to one side of the arm G by the train mechanism causes a turning of 15 the drum J and shaft J', so that the collar J³ imparts a swinging motion to the pointer N, whereby the pin L⁹ held in the flange L⁷ and pointer N is sheared off, the pointer and collar J³ then moving into the position shown in 20 Fig. 6. When the several parts are in this position, the lever L is locked in place, as the turning of the collar J³ moves the latter's notch J⁴ out of register with the lug L⁵ so that the lever cannot be swung outwardly by the operator to disengage the lug L³ from the notch H⁶, 25 and the fixed flange H⁷. Now, in order to reset the device, the operator must first turn the shaft J' back with a wrench or other suitable tool applied on the front or rear end of the shaft 30 J', so as to turn the collar J³ to move its notch J² again in register and engagement with the lower end N' of the pointer N, the latter being turned back by the operator to engage its end N' with the notch J². On the further turning 35 of the shaft J', in the direction mentioned, the pointer N is moved by the collar J³ back to its normal vertical position. A new pin L⁹ is then inserted in the registering aperture in the pointer N and flange L⁷ to lock the latter two 40 parts together. The turning of the collar J³ back to its normal position as described, again brings its recess J⁴ into alignment with the notch L⁶ and lug L⁵, so that the lever L can then again be swung outward a short distance 45 to disengage the lug L³ from the notch H⁶, so as to permit the operator to swing the lever L upward if desired and for the purpose above described.

In order to indicate the direction in which 50 the train is coming, I provide a pointer O pointing in the direction in which the train is moving along the track at the time the lever L is in an uppermost or "no danger" position. When the lever is in a "danger" position, as 55 shown in Figs. 1 and 2, then the pointer O stands vertically in alignment with the pointer N. The pointer O as illustrated in Figs. 6 and 7, is secured on the outer end of a transversely-extending shaft O' mounted to turn in suitable 60 bearings in the housing H⁵. On this shaft O' is secured a cam O² formed with a notch O³ adapted to be engaged by a pin O⁴ projecting from the face of a disk O⁵ secured on the shaft J' and preferably forming one of the 65 flanges of the drum J, as illustrated in Figs. 7 and 8. The cam O² is formed on its under side with two segmental surfaces adapted to

ride on a segmental flange O⁶ projecting from the disk O⁵, so that an accidental displacement of the pointer O is prevented, as the latter cannot be turned until the pin O⁴ engages the notch O³ of the cam O². Now, when the handle lever L is in a lowermost position, as shown in Figs. 1 and 2, then the pin O⁴ engages the notch O³ and when the lever L is swung in an upward direction, either to the right or left, then the turning of the shaft J' and drum J, causes the pin O⁴ to impart a swinging movement to the cam O², whereby the shaft O' is turned and the pointer O is moved to the left, 70 when the handle lever L is moved upward to the left, and the pointer O is moved to the right in case the handle lever L is moved upward to the right. Thus, when the pointer is turned to the right it indicates that the train 75 is coming from the right hand direction and when turned to the left, as shown in Fig. 3, it indicates that the train is coming from the left. When the switch or draw is to be opened then the hand lever L is swung from an uppermost 80 position into a lowermost position, as shown in Figs. 1 and 2, whereby the switch is opened or the draw is unlocked, and at the same time the arm G is swung into a lowermost or "danger" position to bring the said arm into the 85 path of the point F' to actuate the same as previously mentioned, and to be actuated by an additional arm, as hereinafter more fully described. In case the arm G is then forcibly 90 swung into an angular position by the projection or arm carried along by the locomotive, then the shaft G' is turned and the pin L⁹ is sheared off, as above described. The mechanism in the housing H⁵ must then be 95 reset, as above described, to unlock the lever 100 L and to enable the operator to then manipulate the said lever for closing or opening the switch for locking or unlocking the draw and for setting the arm G correspondingly.

In order to actuate the throttle lever P for 105 shutting off the steam from the locomotive engines by the mechanism above described, I provide the train pipe E with a branch pipe E² connected by the usual Westinghouse triple valve mechanism and auxiliary air reservoir 110 with a cylinder Q similar to the ordinary brake cylinder and preferably arranged in the cab of the locomotive A, as shown in Fig. 1. The said cylinder Q contains a piston Q' on which presses a spring Q² held in the said cylinder 115 and coiled around the piston rod Q³ extending outward from the piston Q'. The outer end of this piston rod Q³ has its bearing in a fixed sleeve Q⁴ in which screws a screw Q⁵ so as to limit the outward traveling motion of 120 the piston rod Q³. An apertured cross head Q⁶ is secured on the piston rod Q³ and is engaged by the lower end of a lever R provided 125 at its upper end with a pin R' extending into a slot R² formed in a link R³ pivotally-connected with the usual bell crank lever P' actuated by a hand lever of the throttle lever 130 P in the usual manner. Now, it will be seen that the throttle lever P, see Figs. 12 and 13,

can be manipulated in the usual manner by the engineer in charge of the locomotive as the link R^3 , by its slot R^2 , travels loosely over the pin R' of the lever R .

- 5 It is understood that the throttle lever P , as shown in Fig. 12 is in such a position as to hold the throttle valve fully opened and when moved to the right commences to close the throttle valve to shut off the steam to the 10 cylinders of the engine. As soon as the air is discharged by opening the valve D^3 as previously explained, then the triple valve in the pipe E^2 is actuated in the usual manner, whereby air from the auxiliary reservoir is 15 forced into the cylinder Q so that the piston Q' is moved in the inverse direction of the arrow b' , whereby the cross head Q^6 imparts a swinging motion to the lever R , and the latter, by its connection with the link R^3 , 20 pulls on the throttle lever P , so as to close the throttle valve, thus shutting off the steam from the cylinders of the locomotive engine. The spring Q^2 is compressed by the movement of the piston Q' , as described, and as soon as 25 the auxiliary reservoir is again cut off from the cylinder Q in the usual manner, then the spring Q' returns the piston to the position shown in Fig. 12, thereby leaving the throttle lever P free to be opened and closed by the 30 engineer in charge, without disturbing the lever and the parts connected with the same, in relation to the cylinder Q .

It will be seen that by the mechanism above described, the train is brought to a standstill 35 by applying the brakes and shutting off the steam from the locomotive cylinders, as soon as the point F' of the lever F strikes the arm G , the latter being in the path of the said point at the time the switch or draw is opened.

- 40 In order to impart a swinging motion to the arm G after the latter has actuated the point F' of the lever F , as described, to accomplish the applying of the brakes and the shutting off of the steam, as described, I arrange two 45 levers S and S' on opposite sides of the point F' , the said levers being arranged to freely swing inward at their upper ends, toward the point F' , but being prevented from swinging outward by striking the brackets on which 50 they are fulcrumed. Each of the levers S and S' carries a weight S^2 so as to hold each lever in the proper position, and the lower, weight- 55 ed ends of the levers are pivotally connected with each other by links S^3 and S^4 respectively, as is plainly shown in Fig. 1. Now, it will be seen that when the locomotive A moves forward in the direction of the arrow a' , then the lever S first strikes the downwardly-extending arm G , in case there is danger ahead, 60 so that the lever S swings inward toward the point F' without disturbing the position of the arm G . The latter, when reached by the point F' standing in a vertical position, causes the lever F to swing to the right, in the direction of the arrow c' , as shown in Fig. 1, so 65 that the brakes are applied and the steam is shut off from the engines in the manner above

described. The arm G is then engaged by the other lever S' , and as the latter cannot swing outward at its upper end it causes the 70 arm G to swing in an angular position, thus causing a turning of the shaft G' , and a consequent change in the position of the several parts on the housing H^2 so that the said several parts have to be reset by the operator in 75 charge of the switch and draw, as previously explained.

By supporting the cylinder D for the air outlet valve directly from the axle of the tender A' , and supporting the arm G from 80 the ties of the track on the bracket H , any variation in the track caused by settling of the same, or any variation in the load of the tender or locomotive, will not disturb the relative positions of the point F' and the said 85 arm G , so that the device will always be in proper working order.

I do not claim the track mechanism for actuating the brake mechanism, in this application, as I am about filing a separate application therefor, but merely describe and illustrate said track mechanism in order that my entire invention may be understood.

Having thus fully described my invention, I claim as new and desire to secure by Letters 95 Patent—

1. A train stopping mechanism comprising a valve connected with the train pipe to let air out of the same to apply the brakes, means for inflexibly supporting the said valve direct from the axle of the locomotive or tender, and a lever for the said valve and adapted to be actuated from a track mechanism, substantially as shown and described.

2. A train stopping device comprising a cylinder containing a valve connected with the train pipe and provided with an operating lever adapted to be actuated by a track mechanism, a cross head supporting the said cylinder and provided with an arm, a rod pivotally connected with the said arm and provided with a head, and a casing loosely mounted on one of the axles and engaging the said head, substantially as shown and described.

3. A train stopping device comprising a cylinder containing a valve connected with the train pipe and provided with an operating lever adapted to be actuated by a track mechanism, a cross head supporting the said cylinder and provided with an arm, a rod pivotally connected with the said arm and provided with a head, and a casing loosely mounted on one of the axles and engaging the said head, substantially as shown and described.

4. In a train stopping device, the combination with a cylinder containing a rotary valve and connected with the train pipe to let air out of the same, a lever held on the stem of the said valve and adapted to be engaged by a track mechanism, a spring pressed pin held in the said lever and a fixed notched segment adapted to be engaged by the said spring pressed pin to hold the said lever in position until swung to one side when engaging the

said track mechanism substantially as shown and described.

5. In a train stopping device, the combination of a lever adapted to be shifted by the arm of a track mechanism, a valve carrying the said lever and connected with the train pipe, and levers mounted on the sides of the said lever for the valve and adapted to swing

inward toward the said lever and also adapted to be engaged by the said arm, substantially as shown and described.
